MEANS FOR DETERMINING SCREEN SIZE
FOR WELL SCREENSMelvin J. Napier, Akron, Ohio, assignor to Miami
Boiler & Machine Company, Inc., Akron, Ohio,
a corporation of Ohio

Application August 2, 1950, Serial No. 177,236

4 Claims. (Cl. 73—432)

1

This invention relates to well drilling and, in particular, to means for readily determining the proper size of openings in screens to be inserted in the pipes sunk into water-bearing sands.

In the drilling of wells a pipe is driven by degrees into the ground, which is prepared by a bit working in advance of the pipe. From time to time, samples of the water in the pipe, with suspended matter, are brought to the surface by suitable means and examined to determine the nature of the strata in which the bottom of the pipe is located, until a sand strata is indicated. The underground structure is then completed by dropping a tubular well screen through the pipe into the sand strata, raising the pipe to the top of the screen to uncover it, and securing the bottom of the pipe to the top of the screen tube. Thereafter, the sand surrounding the screen is conditioned by what is known as surging, wherein the water of the sand is worked back and forth through the screen, from the sand into the tube and back out of the tube into the sand. In this operation the finer sand is worked away until a zone of only the coarser sand particles is built up around the screen. This condition persists thereafter and water which is free of fine sand may thereafter be drawn into the well pipe.

In order to achieve maximum rate of volume delivery of water, the screen size must be adapted to the particle size characteristics of the sand and it has become accepted as a rule of thumb that optimum delivery may be expected if the fraction of sand retained by the screen represents 40% of the total sand.

Heretofore, in the selection of proper screen size, the drillers have either estimated the particle size analysis by inspection of a sample at the well site or have actually performed analyses with screens. In the latter method, the sand has to be dried and then shaken through a screen. The first method of estimation is liable to large errors which may entail subsequent replacement of a screen placed in the well pipe. The second is time consuming and does not reproduce actual conditions in the well under surging. The problem is so critical that drillers have frequently sent samples to remote laboratories for screen analysis. This latter method, while representing by far the largest time delay of the three, is also unreliable as failing to reflect actual conditions in the surging operation, and the recommendations as to screen size have been known to be so far in error as to require subsequent replacement of the screen.

2

By the present invention, I have provided for accurately determining proper screen size in a minimum of time at the site of the well by reproducing the actual conditions of surging in a test apparatus.

It is, therefore, an object of the invention to provide for determination of reliable test data relative to screen sizes for wells. A further object is to provide for test data as to screen size for sands in wells, in a minimum of time, at the well site, by simple and inexpensive equipment which does not require special skill in the handling. In particular it is an object to provide means for screen size determination by reproducing conditions of actual well operation. More specifically, it is an object to determine proper well screen size by surging water back and forth through a test screen similar to an actual well screen.

These and other objects will be apparent to those skilled in the art from the accompanying description of the invention as illustrated in the drawings, in which:

Fig. 1 is a side elevation in partial axial section of a test screen, in place in a sand-holding cup,

Fig. 2 is a top plan view of the parts shown in Fig. 1,

Fig. 3 is an elevational view of a test apparatus being immersed in water,

Fig. 4 is a view similar to Fig. 3, showing the test apparatus being lifted out of the water, after a plurality of immersions,

Fig. 5 is a sectional view taken on the line 5—5 of Fig. 3, and

Fig. 6 is a sectional view taken on the line 6—6 of Fig. 4.

Referring to the drawings by characters of reference, there is shown in Figs. 1 and 2, a test screen 10 of cylindrical form, which is a foreshortened length of screen of the type permanently installed in well pipes. The particular screen chosen for illustration is composed of copper tubing of $\frac{1}{8}$ inch wall thickness, $3\frac{1}{2}$ inches outside diameter, and 3 inches in length.

The screen openings are provided in a circumferentially arranged series of louvers, comprising strips 11 outwardly struck from the cylinder 10. Strips 11 are about $\frac{1}{8}$ inches wide, are spaced apart a distance about equal to their width and the openings are about $\frac{3}{4}$ inch in height. The outward radial distance of louvers 11 from the surface of tube 10 determined the size of screen opening and, in actual well screens, this will vary with the grain size of the sands in which the

screen is to be used, the range of sizes of openings being from about 0.003 inch to 0.050 inch. It will be understood that the screen pattern is conventional and forms no part of the present invention. In the actual well screens, the circumferential series of louvers are provided in plurality along the tube, but in the test screen only one such ring of louvers is necessary, and in fact it is preferable to use one only.

The louvers are spaced from the bottom, to provide a lower margin 12, adapted for insertion in snug relation in the depending neck 13 of a cup 14. The latter is cylindrical and concentric with and spaced from screen tube 10. Cup 14 and neck 13 are joined by an annular shelf 16, against which louvers 11 abut to limit movement of screen 10 through neck 13.

The space 17 between tube 10 and cup 14 forms an annular chamber to hold the sand sample and if lower margin 12 of tube 10 is snugly fitted in neck 13 of the cup, the only communication from chamber 17 to the inside of the tube is through the openings at the louvers.

The cup shown has a wall thickness of about $\frac{1}{32}$ inch, the diameter of the larger, upper portion is about five inches, which provides a width of about $\frac{3}{4}$ inch in the chamber 17, and the inner diameter of neck 13 is just enough larger than the outer diameter of tube 10 to provide a sliding fit, without passing fine sand. Tube 10 preferably extends slightly above cup 14, so that the tube may be conveniently grasped by the fingers at the extremities of a diameter when inserting it into or removing it from the cup. The bottom of tube 10 preferably terminates short of the bottom of cup neck 13, so that the position of the screen openings relative to the cup will not be accidentally displaced.

If the chamber 17 be filled with a sample of sand from the well, conditions of actual use of the screen may be simulated. Thus, assuming that in the drilling of a well a likely looking sand strata has been reached, a sampling is made in conventional manner and is placed in the chamber 17 of the test apparatus, in any predetermined, standard amount, up to a reference line, or to the top of cup 14. The sand is in fully dispersed condition, respecting size distribution, as it existed in the sand strata.

The next step is to separate the fine sand from the aggregate by surging, in simulation of the actual process by which the fine sand is eliminated and the coarser particles piled up about the screen openings in the well itself. This step in the test method is illustrated in Figs. 3 and 4. In Fig. 3, the test unit is shown as being immersed in a body of water 18 contained in any convenient vessel 19, such as an ordinary bucket. As shown by the arrows, the water passes within tube 10 and through the louver openings into the sand-filled chamber 17. The sand is indicated by the numeral 21 and Fig. 3 illustrates the first immersion of the unit with the sand particles still randomly dispersed. As the water passes into the sand, it carries the fine particles away from the openings and agitates the coarser particles so that they rearrange themselves in a manner which becomes more or less permanent in pattern with each successive immersion cycle or surging operation. Following immersion, the test unit is lifted from the water, as illustrated in Fig. 4, whereupon the water in the sand 21 drains off through the screen openings, carrying with it the finer sands, which pass

through the interstices among the coarser sand particles.

After a number of cycles of immersion and withdrawal, the sand content in chamber 17 will have reached a condition wherein all of the fine particles which are capable of passing through the array of coarse particles piled up at the screen openings, have passed out of the test unit. This is the condition shown in Fig. 4. The percentage of sand remaining in the chamber can easily and readily be determined by inspection, from its height in the chamber, and drying and weighing are therefore unnecessary.

In the use of the apparatus, the test screens 10 will be provided in a series with different sizes of openings. For any given sample, a test screen may be selected after rough estimation of the character of the sand, and a test run made. If more than 60% of the sand is lost, a smaller screen opening is tried, and if less than 60% of the sand is lost, a larger screen opening is tried, and so on, until the proper screen size is determined. Of course, the 40%-60% standard is arbitrary, but the method is qualified to give accurate data, regardless of the standard employed. On the average, determination of proper screen size, according to this invention, may be made in from one to three minutes.

Although the rings of louvers occur in plurality in the actual well screens, it is preferable to use only one in the test cylinder, since any louvers at higher levels would be utilized only during a part of the filling and draining processes and the results would be less likely to reflect actual conditions.

The present invention is to be distinguished from conventional fractionation practice in the analysis of aggregates. In such cases, fractions are completely separated, in so far as possible. In the use of well screens, where the force tending to move the particles through a screen is a moving stream of water, the retained particles are not necessarily larger than the screen openings, since particles smaller than such openings may, and in fact do, jam up in such a way as to interlock and resist passage of particles which would otherwise pass through the screen. Thus, in using a test method which simulates the surging through well screens, the invention not only gives valuable test data but employs a screening test device which is novel in the art of testing.

Although outwardly struck, vertical louvers have been shown, other types of screen are employed in wells, which are also conditioned by surging. Therefore, the method and apparatus shown and described herein are not limited to the type of screen shown. Also, the screen and cup may be integral, but it is preferable to have a single cup for a series of test screens. In general, changes may be made in the size, shape, and arrangement, for instance, of the various parts of the present invention, without departing from the spirit or scope of the appended claims.

65. What is claimed is:

1. A portable test unit for determining suitable well screen size for a given well, comprising a right, circular, cylindrical element having outwardly struck portions defining openings through the wall of said element, and a right, circular, cylindrical imperforate receiving member for said element having a portion spaced outwardly of said element to define an annular chamber, and a portion receiving a free end of said element in a close, sliding fit, said struck

portions being arranged circumferentially about said element and extending into said chamber so as to limit the extent of movement of said element into said second-mentioned portion.

2. For use with a section of cylindrical well screen, for determining suitability of the screen size for a given well, a portable, right, circular, cylindrical receiving member for holding a quantity of sand in surrounding relation to said screen, said member being entirely imperforate and comprising a first, cylindrical portion, a second, cylindrical portion concentric with and of smaller diameter than said first portion, and an annular wall connecting said portions, said portions being disposed on opposite sides of said annular wall, and said portion of smaller diameter adapted to receive a section of well screen in a close, sliding fit.

3. A portable test unit for determining suitable well screen size for a given well, comprising a right, circular, cylindrical element having wall openings to provide a screen, a right, circular, cylindrical imperforate receiving member for said element, having a portion spaced outwardly of said element to define an annular chamber, and a portion receiving a free end of said element in a close, sliding fit, and means

limiting extent of movement of said element into said receiving portion.

4. A portable test unit for determining suitable well screen size for a given well, comprising a right, circular, cylindrical element having wall openings to provide a screen, a right, circular, cylindrical imperforate receiving member for said element, having a portion spaced outwardly of said element to define an annular chamber, and a portion receiving a free end of said element in a close, sliding fit, and means limiting extent of movement of said element into said receiving portion, with said free end of said member lying within said receiving portion.
